FOLDABLE ELECTRICAL TERMINAL
HAVING LANCESJames Francis Gillespie, Palmyra, Pa., assignor to
AMP Incorporated, Harrisburg, Pa.

Filed Feb. 5, 1971, Ser. No. 112,936

Term of patent 14 years

Int. Cl. D13—03

U.S. Cl. D26—1 E

FIG. 1 is a top side perspective view of a foldable electrical terminal having lances showing my new design;

FIG. 2 is a side elevational view thereof taken from the left side of FIG. 1;

FIG. 3 is a right side elevational view thereof;

FIG. 4 is a front elevational view thereof; and

FIG. 5 is a rear elevational view thereof.

I claim:

The ornamental design for a foldable electrical terminal having lances, as shown and described.
